ATTORNEY.

UNITED STATES PATENT OFFICE.

RUSSELL H. LEWIS, OF PROVIDENCE, RHODE ISLAND, ASSIGNOR OF ONE-HALF, TO HERBERT A. THAYER, OF PROVIDENCE, RHODE ISLAND.

BRACELET.

No. 918,175.

Specification of Letters Patent. Patented April 13, 1909.

Application filed October 19, 1908. Serial No. 458,506.

To all whom it may concern:

Be it known that I, RUSSELL H. LEWIS, a citizen of the United States, residing at Providence, in the county of Providence and State of Rhode Island, have invented certain new and useful Improvements in Bracelets, of which the following is a specification.

My invention relates to bracelets composed of a plurality of connected expandible units, and has for its objects the provision of easily slidable connecting members; a novel and secure mounting for the springs adapted for facile reception thereof; and an inexpensive and strong means for preventing excessive distention of the springs.

Figure 1 is a plan elevation of a bracelet embodying my invention, Fig. 2, a vertical central section of a portion of the bracelet showing the parts in contracted position, Fig. 3, a like section of the same showing the parts expanded, Figs. 4 and 5, sections on line $x-x$ of Fig. 2 and on $y-y$ of Fig. 3 respectively, Fig. 6, a perspective view of one of the units with its face plate removed, and Fig. 7, a perspective view of one of the connecting members.

Like characters of reference indicate like parts throughout the views.

30 My bracelet comprises a series of shells or units, A, expansibly connected by members hereinafter described. In detail, the units are composed of the inner and outer walls, a and a' , the former being preferably curved; also end walls, a^2 and a^3 , preferably inclined; and side walls, a^4 and a^5 . In manufacture, it is convenient to form the walls, a , a^2 , a^3 , a^4 , and a^5 in one piece, and solder or otherwise fix the front wall or plate, a' , to the side and end walls.

40 The end walls, a^2 and a^3 are provided respectively with vertically disposed oblong slots or openings, a^6 and a^7 .

The connecting members, B, consist of a series of flat plates, links, or frames struck up out of sheet metal. They are substantially rectangular in outline and in detail are of the following construction. One end of the plate, B, is provided with lateral lugs or projections, b , b . Upon each side of its center the plate is cut out to form two parallel longitudinal slots, b' , b^2 , and a transverse slot, b^3 , connecting the longitudinal slots at about one-third their length, which form oppositely disposed integral long and short

projections, b^4 and b^5 respectively. In the 55 plate at a point intermediate the slots, b^2 , b^3 is cut a tongue, C, whose end extends out of the plane of the plate and is purposed as a stop.

In assembling the members, A and B, the 60 latter is passed through the slots, a^6 and a^7 of adjacent unit walls until the lugs, b , b of the frame abut against the inner face of the wall a^2 in each case. The tongue, C, which is of springy material and directed toward 65 the end of the plate, B, which carries the lugs, b , presents no obstruction to the described introduction of the plate.

Upon each pair of projections, b^4 , b^5 is mounted a helical spring, D. These are applied by introducing one end of the spring through the slot, b^3 and over and along the projection, b^4 , and compressing the coils thereon sufficiently to permit the other end of the spring to be brought into alinement 75 with the projection, b^5 , whereupon the spring is released and surrounds the latter projection. The projections upon which the springs are thus mounted form a stiff guide, bearing, and support throughout their length 80 which prevents buckling, strain, and dislodgment. One end of each spring rests against the portion of the plate adjacent the base of the projection, b^5 , while its other end bears against the inner face of the end wall, 85 a^3 . Excessive longitudinal strain upon the springs which might otherwise result in setting the same, is prevented when the units are expanded by the contact of the free end of the tongue, C, against the inner face of the 90 wall, a^3 .

It will be noted that the several parts are simply and inexpensively constructed, and easily assembled.

The lateral lugs, b , may be omitted, and 95 the slots, b^2 , may be extended to one of the end margins of the plate, B, without departing from the spirit of my invention; but obviously with some resulting irregularity in the outline of the bracelet, and with a loss of 100 strength in the plate.

Other changes and modifications of my invention will occur to those skilled in the art.

What I claim is,

1. In a bracelet, a connecting link, projections in the link in longitudinal alinement with each other, and an actuating spring upon the projections. 105

2. In a bracelet, a flat connecting link, oppositely disposed projections in the link, an actuating spring upon the projections, and a tongue upon the face of the link.
- 5 3. In a bracelet, a flat connecting link oppositely disposed integral projections upon the link and in the plane of the link, an actuating spring mounted upon the projections, and an integral tongue upon an intermediate 10 portion of the link projecting out of the plane of the link.
- 15 4. In a bracelet, a flat connecting link provided with lateral lugs, oppositely disposed projections in the link, and an actuating 20 spring upon the projections.
5. In a bracelet, a flat connecting link provided with integral lateral lugs, oppositely disposed integral projections upon the link and in the plane of the link, an actuating 25 spring mounted upon the projections, and an integral tongue upon an intermediate portion of the link.
6. In a bracelet, a flat connecting link provided with an opening integral projections upon the link extending into the opening, a spring upon the projections, and a stopping 30 device upon an intermediate portion of the link.
7. A bracelet composed of a plurality of expandible units, each unit consisting of a shell, a flat connecting link slidably mounted in the shell and provided with oblong openings, oppositely disposed projections in the link extending into each of the openings, a spring in each opening mounted upon the 35 projections and stopping means upon the link.
8. A bracelet composed of a plurality of expandible units, each unit consisting of a shell, a flat connecting link slidably mounted 40 in the shell and provided upon opposite sides of its center with oblong openings, projections in the link extending into each of the openings, a spring in each opening mounted upon the projections, and a stopping device 45 in the link intermediate the openings.

In testimony whereof I have affixed my signature in presence of two witnesses.

RUSSELL H. LEWIS.
